UNITED STATES PATENT OFFICE.

HULDA DUSOLD, OF MILWAUKEE, WISCONSIN.

CURTAIN FASTENER.

Application filed March 20, 1926. Serial No. 96,216.

This invention relates to improvements in curtain fasteners.

Curtains of various kinds now in use have rings in spaced relation, sewed to their upper edges for slideable engagement with the curtain rod upon which they are mounted. In traversing curtains, cords are attached to the upper edge portions of the curtains and extend over pulleys to permit the easy drawing or traversing of a pair of curtains on a rod. To remove the curtains for cleaning purposes, it is necessary to disconnect the cords from the pulleys and the rings from the rods and after cleaning, the parts have to be replaced. This is very difficult for the average housewife and generally the services of a professional man are required to take down or replace the parts. Furthermore the rings sewed to the upper edges of the curtains are objectionable due to the fact that the rings become bent or otherwise damaged during the washing operation.

It is one of the objects of the present invention to overcome the before mentioned objectionable features and provide a curtain fastener formed of two parts, one of which may be easily and permanently attached to a curtain while the other portion is easily detachably connected to the attached portion.

A further object of the invention is to provide a curtain fastener which will permit the easy removal of a curtain from its support without the necessity of removing the curtain rings from the curtain pole or other support.

A further object of the invention is to provide a curtain fastener which can be sold independently of the curtains and in any desired length and arranged for easy attachment to any curtain or other material.

A further object of the invention is to provide a curtain fastener which is adapted for use with all kinds of curtains, drapes and hangings which are hung on rings suspended from poles or other supports, to materially simplify the hanging and removal of same.

A further object of the invention is to provide a curtain fastener having means for preventing the fasteners from catching on shoulders or other obstructions formed on tele-

scopic rods upon which the fasteners are usually slidably mounted.

A further object of the invention is to provide a curtain fastener which is of very simple, strong and durable construction, is inexpensive to manufacture and is easily attached, and is well adapted for the purpose described.

With the above and other objects in view, the invention consists of the improved curtain fastener and its parts and combinations as set forth in the claims, and all equivalents thereof.

In the accompanying drawing in which the same reference characters indicate the same parts in all of the views:

Fig. 1 is a side view showing the improved curtain fastener attached to a curtain and mounted on a rod;

Fig. 2 is a top edge view of the curtain and the detachable curtain fastener;

Fig. 3 is a fragmentary front view thereof on a larger scale;

Fig. 4 is a side view of the curtain fastener ready for application to the curtain;

Fig. 5 is a transverse sectional view taken on line 5—5 of Fig. 4 but taken on a larger scale;

Fig. 6 is a side view of a modified form of ring;

Fig. 7 is a side view of another modified form of fastener provided with rollers to eliminate friction and prevent catching on shoulders or other obstructions;

Fig. 8 is a vertical sectional view thereof taken on line 8—8 of Fig. 7;

Fig. 9 is a transverse sectional view taken on line 9—9 of Fig. 7;

Fig. 10 is a side view of another modified form of fastener;

Fig. 11 is a longitudinal sectional view thereof taken on line 11 of Fig. 10 and shown mounted on a telescopic rod; and

Fig. 12 is a transverse sectional view thereof taken on line 12 of Fig. 10.

Referring to the drawing, the numeral 8 indicates a door or window frame, 9 a curtain rod extending from one side of the opening to the other, and 10 a pair of curtains sus-

pended from said rod by a plurality of rings 11. Cords 12, extending over pulleys 13 are connected to the curtains in a manner to cause the curtains to traverse on the rod when the 5 cords are pulled.

Traversing curtains or drapes now in ordinary use have the supporting rings sewed directly to the upper edges of the curtains with the result that when it is necessary to 10 remove the curtains for laundering or cleaning purposes, the operating cords are detached, the rods removed and the curtains removed from the rod. This is a complicated operation for persons unskilled in the art, 15 and especially the reverse operation of hanging the curtains and connecting the traversing cords, and an expert is usually called in to connect up the parts so they will operate properly.

20 In the present invention, the mentioned objectionable features are eliminated and the curtains or drapes are suspended in a very simple manner so that they may be readily detached or hung without removing the rings 25 from the rod, or disturbing the cords. To accomplish this result, the rings 11 having shank portions 13 are preferably stamped from sheet metal and the shank portions 13 are given a one-quarter turn so that the lower 30 eyed portions 14 will be in a plane at right angles to the plane of the ring portion 11. The said eyed portions are firmly mounted in spaced relation on a strip of tape 15 by means of the projecting head portions 16 of 35 snap fastener members 17. A complementary strip of tape 18 adapted to be sewed to the upper edge portions of the curtains or other drapery by lines of stitching 19, has connected thereto complementary snap members 20 which are spaced apart to register 40 with the snap member 17. Said snap members 20 are constructed to receive the projecting head portions 16 of the snap fastener members 17 to detachably connect the curtain or other drapery to the ring tape 15. The strips with the fasteners and rings 45 mounted thereon can be provided in any color and length to be sold by the yard so that the purchaser may buy the desired color and length to match and fit the curtains or 50 drapery.

In the modified form shown in Fig. 6, the ring member is of elongated rectangular form as indicated by the numeral 21 to fit 55 rods of rectangular form in cross section.

In the event that the fasteners are used on telescopic rods, it is necessary to prevent the fasteners from catching on the end edges of the telescopic sections, and to accomplish this 60 result the modified forms shown in Figs. 7 to 12 inclusive are provided. In the form shown in Figs. 7, 8 and 9, the upper portion 22 and the side portions 23 of the part 21 are reduced in width to form bearings upon 65 which are journaled split rollers 24 and 25

formed from sheet metal. The rollers are of sufficient diameter to easily roll over the shoulder 26 formed on telescopic rod sections 27 shown in Fig. 11. The shoulders 23' formed by reducing the width of the bearing 70 portions of the fasteners prevent endwise movement of the rollers.

In the modified form shown in Figs. 10, 11 and 12, side and top inner edge portions of the fasteners are folded over to form rounded 75 bearing surfaces 28 and 29 which will easily ride over the shoulders formed by the telescoping sections before mentioned.

It is to be understood that the curtain fastener is applicable for use in suspending 80 all forms of drapery such as curtains, portières and other hangings, with the weight of the drapery suspended directly from the suspension members.

From the foregoing description, it will be 85 seen that the improved curtain fastener is of very simple construction and is well adapted for the purpose described.

What I claim as my invention is:

1. A curtain fastener, comprising two 90 elongated strips of material, complementary fastening members easily detachably connecting the strips together at a plurality of points, and suspension members rigidly and directly connected to and forming part of the fastening members on one of the strips.

2. A curtain fastener, comprising an elongated strip of material, snap fastener members connected to the strip in spaced relation and having projecting head portions, suspension members, having rigidly depending shank portions directly connected to the snap fastener members, a second elongated strip of material for attachment to drapery, and complementary snap fastener members connected to the second strip of material in spaced relation for receiving the heads of the first-mentioned snap fastener members for detachably connecting the two strips of material together beneath a supporting rod.

3. A curtain fastener, comprising an elongated strip of material, snap fastener members connected to the strip in spaced relation and having projecting head portions, suspension members having eyed shank portions directly connected to the snap fastener members, the head portions of which extend through the eyes of the shanks, a second elongated strip of material for attachment to drapery, and complementary snap fastener members connected to the second strip of material in spaced relation for receiving the heads of the first-mentioned snap fastener members for detachably connecting the two strips of material together.

4. A curtain fastener, comprising an elongated strip of material, snap fastener members connected to the strip in spaced relation and having projecting head portions, ring suspension members having rigidly de-

pending eyed shank portions directly connected to and extending at right angles to the snap fastener members, the head portions of which extend through the eyes of the shanks, the plane of the ring portion extending at right angles to the plane of the eyed shank portions, a second elongated piece of material for attachment to drapery, and com-

plementary snap fastener members connected to the second strip of material in spaced relation for receiving the heads of the first mentioned snap fastener members for detachably connecting the two strips of material together. ¹⁰

In testimony whereof, I affix my signature.

HULDA DUSOLD.
